J. A. MILLEA,
DEVICE FOR STAMPING NAMES OR NUMBERS,
APPLICATION FILED JULY 23, 1917.

Patented Apr. 16, 1918.

FIG. 1

FIG. 2

FIG. 3

INVENTOR

John A. Millea by
Frederick W. Cameron,
ATTORNEY

UNITED STATES PATENT OFFICE.

JOHN A. MILLEA, OF RENSSELAER, NEW YORK.

DEVICE FOR STAMPING NAMES OR NUMBERS.

1,263,094.

Specification of Letters Patent. Patented Apr. 16, 1918.

Application filed July 23, 1917. Serial No. 132,154.

To all whom it may concern:

Be it known that I, JOHN A. MILLEA, a citizen of the United States of America, residing at the city of Rensselaer, in the county of Rensselaer and State of New York, have invented certain new and useful Improvements in Devices for Stamping Names or Numbers, of which the following is a specification.

10 My invention relates to devices for stamping names or numbers, and the object of my invention is to provide an ink container, rubber stamp and inking pad which, when out of use, may be so arranged as to be capable of being carried in a pocket without the ink from the die or pad coming in contact with the pocket; together with such other elements and combinations as are herein-after more particularly set forth.

20 I accomplish these objects as illustrated in the accompanying drawing, in which:

Figure 1 is a perspective view of my ink container and stamp.

Fig. 2 is a perspective view of the pad and cover for the stamp.

Fig. 3 is a perspective view of the parts shown in Figs. 1 and 2 when placed together.

Similar letters refer to similar parts throughout the several views.

30 For the purpose of holding a rubber stamp, A, and a bottle or ink container, G, I bend a piece of thin metal so as to form a flattened portion, B, to which the rubber stamp, A, is attached, turning the metal up along one edge at C to form a flange, as shown in Fig. 1. I bend the metal upwardly away from the flattened portion, B, forming a retreating upwardly projecting portion, D, and then I curve the plate outwardly, bending it upon itself forming a circular portion, E. I then bend the plate downwardly and outwardly forming a portion, F, the lower edge of which engages with the flange, C. Into the opening formed by the curved portion, E, I insert the ink container or bottle, G, which is preferably closed by means of a threaded cap, H.

For the purpose of inking the rubber stamp, A, I provide an inking pad, J, which is secured in the metal plate, K, a flange,

j, projecting around the edges of the plate forming a recess for the pad. In order to make a cover for the rubber stamp and means for locking the pad containing member with the stamp containing member, I 55 bend the metal plate, K, at an angle to the plate, K, forming a flange, L, and then bend the plate upon itself extending in a direction toward the face of the pad plate a short distance, and then curve the plate upwardly 60 and bend it upon itself forming a lip, M. I then bend it at substantially right angles at N, extending beneath the lip, M, forming a flattened portion, O, and extending a sufficient distance to form a cover for the portion, B, containing the stamp, A, then bend it upwardly and curve it inwardly to form an overhanging lip, P.

As thus arranged, the ink container and rubber stamp may be placed and held together, when out of use, with both the stamp and pad protected. This is done by inserting the ink container into connection with the pad plate by directing the flange, C, into the recess, R, and the lower curved edge of 75 the side, D, under the lip, P, then slipping the two parts together from end to end.

Where I refer to "rubber" stamp herein, I mean to include those made of any other material as well. I do not limit myself to 80 the exact construction of the parts as illustrated and described.

What I claim as my invention and desire to secure by Letters Patent is:

A stamp; a plate to which the stamp is 85 attached; said plate bent to form a longitudinal opening parallel to the axis of the stamp, adapted to receive and hold an ink bottle; a cover for said stamp, comprising a casing provided with a pad; and projecting lips on said casing adapted to engage the plate carrying the stamp, whereby both the pad and stamp may be protected when out of use.

In testimony whereof I have affixed my signature in the presence of two witnesses.

JOHN A. MILLEA.

Witnesses:

FREDERICK W. CAMERON,
BEULAH CARLE.
